COLLAR ATTACHMENTS

Kenneth J. Wittenberg, La Crosse, Wis.

Application January 3, 1956, Serial No. 556,922

6 Claims. (Cl. 2—132)

This invention relates to new and useful improvements in collar attachments, and more particularly to such a device adapted for use with soft shirt collars used by the military to retain the wings of such collars in a neat and attractive condition, and having means embodied therein for accurately locating on the collar wings, the usual insignias or ornaments, as required by the military.

It is well known that the military is divided into many different branches of service, such as, for instance, the Corps of Engineers, Infantry, Field Artillery, Quartermaster Corps, and many others. Each such branch of the military service is known by its own specific insignia, which insignias are usually worn on the wings of each serviceman's shirt collar. Officers' ranks, such as Lieutenant, and Captain, are also designated by certain specific ornaments which, in like manner, may be attached to the wings of each officer's shirt collar.

Army regulations require that all such insignias and ornaments must be accurately located on the collar wings, whereby when each such insignia or ornament is attached to a collar wing, it will be spaced downwardly a given distance from the top edge of the collar, and upwardly a similar distance from the bottom edge of the collar wing. It must also be spaced rearwardly a given distance from the front upright edge of the collar wing. This requirement is known in the military as "Standard Operating Procedure," or S. O. P.

To thus accurately locate the various insignias and ornaments on the collars of servicemen's shirts, as now being done, requires considerable time and patience on the part of each serviceman, and it is therefore highly desirable that means be provided for facilitating the operation of attaching the various insignias and ornaments to the wings of soft shirt collars, whereby such operations may be greatly expedited, and with the assurance that all insignias and ornaments will be accurately located on the wings of their respective shirt collars, in accordance with military S. O. P.

An important object of the present invention, therefore, is to provide a collar stay having means embodied therein for quickly and accurately locating and securing a selected insignia or ornament to the wings of a collar, whereby the serviceman may be assured that the attachment of the insignia to his shirt collar will fully meet the requirements of the military S. O. P.

A further object of the invention is to provide a collar stay, including an elongated, longitudinally extensible member comprising an intermediate tubular section, a lower section having one end slidably received in the lower end of said intermediate tubular section and having means at its lower end for engaging the lower tip of a collar wing, and an upper section being secured to the upper end portion of said tubular section and having means at its upper end for engagement within the fold at the upper edge of the collar, spring means being provided within the tubular section for constantly urging the upper and lower ends of the composite stay into operative engagement with the collar wing, whereby the stay may be in-

2

separably secured to the collar wing, thereby to retain the wing taut, and means also being provided on said stay member for facilitating the operation of accurately locating an insignia or ornament on the collar wing.

5 A further object is to provide a combined collar stay and insignia locator which, in addition to keeping a collar wing in its normal extended position, also provides means for quickly accurately locating an insignia or ornament on the collar in accordance with the requirements of the military S. O. P.

10 Other objects of the invention reside in the simple and inexpensive construction of the combined collar stay and insignia locator, whereby it may be manufactured in quantity production at very low cost; in the novel means 15 provided for securing the upper end portion of the composite collar stay to the intermediate tubular section of the composite stay, whereby said upper section cannot relatively rotate with respect to the intermediate tubular section, and also whereby the laterally extending arm which 20 provides the means for accurately locating the insignia or ornament on the collar wing is retained in fixed relation relative to the upper and lower edges of the collar wing; in the provision of such an attachment which is equally useful on collars of the closed or open type; and in the 25 provision of such a device having means for securing the insignia or ornament to the collar, whereby it cannot accidentally become detached therefrom.

These and other objects of the invention and the means for their attainment will be more apparent from the following description taken in connection with the accompanying drawings.

In the accompanying drawings there has been disclosed a structure designed to carry out the various objects of the invention, but it is to be understood that the invention 35 is not confined to the exact features shown, as various changes may be made within the scope of the claims which follow.

In the drawings:

Figure 1 is a view showing one wing of a soft shirt collar with a military ornament properly positioned thereon in accordance with the invention herein disclosed, and 40 in compliance with military S. O. P. (Standard Operating Procedure);

Figure 2 is a view showing the general construction of 45 the composite collar stay, which also functions as a locator for accurately locating an insignia or military ornament on a military shirt collar;

Figure 3 is a sectional view on the line 3—3 of Figure 2;

Figure 4 is a view showing the invention placed against 50 the outer surface of a collar wing, as when utilized to initially locate an insignia or ornament on a collar wing;

Figure 5 is a fragmentary view showing an ornament about to be pressed into locking engagement with a collar wing;

Figure 6 is a view similar to Figure 5, but showing the 55 ornament firmly affixed to the collar wing;

Figure 7 is a view similar to Figure 1, but showing an ornament in the form of a bar;

Figure 8 is a fragmentary view similar to Figure 5, 60 showing a pin-type ornament about to be secured to the wing of a collar in accordance with the present invention; and

Figure 9 is a view similar to Figure 8, but showing the 65 ornament secured to the collar wing.

The novel collar attachment herein disclosed is best illustrated in Figure 2 and comprises a composite collar stay, generally designated by the numeral 2, including an intermediate elongated tubular section 3, a lower section 4, and an upper section 5.

The lower section 4 is provided at its lower end with a spur 6 adapted to pierce the fabric of the tip of the collar

wing, as indicated in Figures 2 and 7. The upper end portion of the lower section 4 is telescopically received within the lower end portion of the intermediate tubular section 3. The upper section 5 of the stay 2 has a head 7 adapted to fit within the fold 8 at the upper edge of the collar, as best illustrated in Figure 2. A suitable spring, not shown, is provided within the tubular member 3 of the stay and is engaged with the inner end of the lower section 4, and thus constantly tends to elongate the stay, thereby to inseparably retain the stay in proper position on the collar wing, as is well known.

A feature of the invention resides in the provision of the laterally extending arm 9 of the upper section 5 which provides the means for accurately locating the insignia or ornament 11 on the collar wing, as shown in Figures 1, 4 and 7. The arm 9 is preferably integrally formed with the upper section 5, and is located in the plane of the head 7. To prevent relative rotation of arm 9 on the tubular member 3 of the composite stay 2, a securing element 12 is provided on the upper end of the intermediate tubular section 3, and initially extends outwardly therefrom, as indicated by the dotted lines in Figure 2. A similar securing element 13 is provided on the intermediate portion of the tubular member 3 and normally is extended as indicated by the dotted lines 14. Securing elements 12 and 13 may, if desired, be integrally formed with the metal from which the tubular section 3 of the composite stay 2 is fabricated.

To secure the combined upper section 5 and laterally extending arm 9 to the tubular member 3, the lower end portion of section 5 is placed against the upper end portion of member 3 and against the extended securing elements 12 and 13. Element 12 is then folded around section 5 and around the upper end of the tubular section 3. The lower extended end portion 14 of securing element 13 is then folded upwardly around the arm portion 9 adjacent to the tubular member 3, as shown in full lines in Figure 2, and said elements are then suitably secured in place, as shown in full lines in Figure 2, by suitable means such as soldering. The upper section 5 and laterally extending arm 9 are thus permanently secured to the tubular section 3 and becomes, in effect, an integral part of the composite stay 2. Securing element 13 also serves as a gusset plate to maintain arm 9 at a fixed angle to the upper section 5, which is necessary to assure that the ornament will be accurately located on the collar wing, when applied thereto.

Another important feature of the present invention resides in the means provided in conjunction with the arm 9 of the stay 2 for accurately locating the various insignias and ornaments on the wings of military shirt collars, as hereinbefore stated.

Such means is shown comprising a circular disk 15 which is rotatably mounted on the outer end of arm 9. To thus mount disk 15 on arm 9, the latter may be provided with a terminal eye 16 adapted to receive a pivot pin or rivet 17 which also is received in an aperture provided in disk 15. Thus, when the collar stay 2 is attached to a collar wing, as shown in Figures 1, 2 and 7, the disk 15 will be located a given distance from the stay 2, and midways between the upper and lower edges of the collar wing, as required by the military S. O. P.

Most military insignias or ornaments usually comprise an outer shell 18, which may be secured to an anchor plate 19 by such means as a stud 21, suitably secured at one end to the shell 18. The projecting end portion of stud 21 may be threaded, as indicated in Figure 5, to facilitate securing it to the anchor plate 19.

The anchor plate 19 of each ornament 18 has secured thereto a pair of spaced prongs or pins 22, the projecting terminals of which are sharpened, as shown in Figure 5, to facilitate forcing the pins through the fabric of the collar wing into locking engagement with a pair of securing devices, generally designated by the numeral 23.

These securing devices are well known in the art, and therefore need not be described in detail herein. Briefly, they frictionally grip the prongs 22, when pressed thereonto into engagement with the locating disk 15 of the present invention. Each securing device 23 is provided with manually operable means for releasing them from their respective prongs 22, when for some reason it becomes necessary to completely detach the collar stay, disk 15 and anchor plate 19 from the collar, as for example, when the collar is to be laundered.

As is well known, the personnel of the various branches of the military service are known by the specific insignias or ornaments worn on their uniforms or shirt collars. These ornaments are of various shapes and sizes, and hence may require slightly different mounting means. As an example, the spacing between the prongs 22 of one ornament may differ from the spacing between the prongs of another ornament, and so on, whereby it may be necessary to provide the locating disk 15 with several pairs of spaced apertures, such as A—A, B—B, C—C, and D—D, as best illustrated in Figures 2 and 7, each such pair of spaced apertures serving to locate a given insignia or emblem on the collar ring.

There may be instances, however, where two or more insignias and/or ornaments may have their mounting prongs spaced the same distance apart. In such cases, a given set of holes A—A, B—B, C—C, or D—D, may serve to locate two or more such ornaments on their respective collar wings. Suitable embossings E—E are also provided in disk 15 to adapt it for locating pin-type ornaments such as illustrated in Figures 8 and 9.

The insignia or emblem 11, shown in Figure 1, is correctly located on the collar wing in accordance with the military "S. O. P." When so located, the spacing *a* between the uppermost portion of the insignia or ornament to the top edge 24 of the collar, and the spacing *b* between the lowermost edge of the ornament to the bottom edge 25 of the collar are the same, or approximately one-half inch. The spacing *c* from the upright front edge 26 of the collar to the nearest edge portion of the ornament or insignia is approximately one inch.

In Figure 7 there is illustrated an officer's bar 27 correctly located on a collar wing, wherein the upper and lower ends of the ornament are spaced equi-distant from the top and bottom edges 24 and 25, respectively, of the collar, as illustrated. The front marginal edge of bar 27 is also spaced one inch from the front edge 26 of the collar wing, as in Figure 1. It will also be noted by reference to Figure 7 that the longitudinal axis of ornament or bar 27 is perpendicular to the upper edge 24 of the collar.

Insignias or ornaments worn by the personnel of the various branches of the military service are now furnished by different manufacturers, and consequently the spacing between the prongs of the insignias or emblems of one manufacturer may not coincide with the spacing provided in the same type of ornament made by another manufacturer. Because of such variations in the spacing between the prongs of given ornaments or insignias made by different manufacturers, the apertures provided in the locating disk 15 must be located therein in accordance with the particular ornaments and insignias to be used. Once the locations of the various sets of apertures have been determined such pairs of apertures may be permanently located in the disks 15 by the manufacturer, as will be understood.

To embody the various pairs of apertures A—A, B—B, C—C and D—D in the disk 15 during manufacture thereof, the manufacturer must first determine the correct locations for said pairs of apertures in disk 15. This may readily be accomplished by first placing the composite device against the top or outer surface of the collar wing as shown in Figure 4, the collar wing preferably being placed upon a flat supporting surface such as a table top,

as will be understood. After the manufacturer has thus determined the correct locations of the apertures A—A, B—B, C—C and D—D in disk 15, the apertures are permanently punched in the disk by suitable dies.

Thereafter, when a serviceman is about to attach an insignia or ornament, such as 11, to his collar wing, he first places the composite device on the top of the collar wing, as shown in Figure 4. The disk 15 is then relatively rotated on arm 9 to bring the selected pair of apertures C—C into registry with pins 22 of insignia 11. The pins 22 are then passed through apertures C—C and into contact with the fabric of the collar wing, whereby pins 22 make indentations in the surface of the fabric, as will be understood. The composite device may then be removed from the top or outer surface of the collar wing, after which the pins 22 of the insignia are forced through the fabric, as shown in the upper portion of Figure 5. The composite device is then placed against the underside of the collar wing with the pins 22 traversing apertures C—C, whereby the collar stay 2 of the composite device will lie directly under seam 28, as best shown in Figure 7. When so positioned, spur 6 of the stay 2 is in piercing engagement with the top of the collar wing and the triangular head 7 at the upper end of the stay is seated in the fold of the upper edge 24 of the collar, whereby the combined collar stay and insignia locator is not likely to accidentally become detached from the wearer's shirt collar.

It is to be understood, of course, that the various pairs of apertures A—A, B—B, C—C and D—D, and also the embossings E—E are so located in disk 15, that when a given insignia or emblem such as 11, is to be attached to a collar, and its spaced prongs 22 are inserted through the fabric of the collar and through the pair of apertures C—C in disk 15, said insignia or emblem will be accurately located on the collar wing, as hereinbefore stated. The rotatable mounting of disk 15 on arm 9 permits the disk to be rotatably adjusted thereon, whereby the different pairs of apertures in disk 15 may be moved into operative positions relative to the collar wing to accurately position thereon the particular insignia or emblem associated with each pair of apertures A—A, B—B, C—C and D—D.

The combined collar stay and emblem locating disk 15 is thus completely concealed behind the collar wing, when in use, as clearly illustrated in Figures 1 and 7. It will also be understood by reference to Figures 5 and 6, that the prongs 22 of emblem 11 pass through the fabric of the collar wing and through apertures C—C in disk 15, and are fixed to disk 15 by the clutching devices 23, as hereinbefore stated.

Figures 8 and 9 illustrate the manner of securing a pin-type ornament to the collar wing by the use of the present invention. As here shown, the collar wing 29 is positioned over the locating disk 15 and the pin 31 of ornament 32 is then inserted through the fabric of the collar wing, and through the embossings E—E and into engagement with the keeper or catch 33 of the ornament, as best shown in Figure 9. When the ornament is so attached to the collar wing, it will be accurately positioned thereon with respect to the three adjacent edges 24, 25 and 26 of the collar wing, and is not likely to accidentally become detached therefrom.

The novel combined collar stay and ornament locator herein disclosed has been found extremely practical in actual use. It functions equally well with open or closed collars, and assures the serviceman that when the ornament is attached to the collar wing, it will be accurately positioned thereon in accordance with the military "S. O. P."

When it becomes necessary to clean and polish the ornament, it may readily be detached from the collar in the usual manner. When so detached from the collar, the holes left in the fabric by the pin 31, or prongs 22,

may readily be noted and will serve as a guide when replacing the ornament on the collar after polishing, and with the assurance that it will be accurately positioned thereon. The collar stay 2 and disk 15 may also readily be detached from the collar wing, when the shirt is to be laundered, by simply releasing the spur 6 of the collar stay from the tip of the collar wing, after which the entire device may readily be removed from the collar.

In the process of laundering the shirt, the holes in the fabric of the collar left by the pin 31, or prongs 22, may disappear from sight because of the threads of the fabric returning to their normal positions. The ornament, however, may readily be returned to its normal position on the collar wing by inserting the pin 31 through the fabric of the collar and through the embossings E—E, as hereinbefore stated, whereby the operation of accurately replacing the ornament on the collar wing becomes a very simple one.

Thus, the device disclosed in the present application serves the dual function of retaining the collar wing in its normal condition, and at the same time provides means for accurately locating the insignia or ornament on the collar wing. The laterally extending arm 9 to which the disk 15 is pivotally secured, is preferably made integral with the upper section 5 of the stay 2, as best illustrated in Figures 2 and 7, and as said section and arm are fixedly secured to the tubular section 3 of the stay by the securing elements or lugs 12 and 13, the section 5 cannot relatively rotate with respect to the intermediate tubular section 3 of the stay, whereby the spur 6 and triangular head 7 of the stay are always properly positioned relative to the collar wing when the device is attached thereto, as shown in Figures 2, 4 and 7 of the drawings.

The foregoing detailed description has been given for clearness of understanding only, and no unnecessary limitations should be understood therefrom, and the appended claims should be construed as broadly as permissible in view of the prior art.

I claim as my invention:

1. In a combined collar stay and ornament locator, an elongated stay member comprising an intermediate tubular section, a lower section having its upper end portion slidably supported in the lower end portion of said tubular section, whereby it may be extended therefrom to engage the tip of a collar wing, said stay also having an upper section fixedly secured thereto and provided with a head for engaging in the fold at the upper edge of a collar, an arm having one end fixedly secured to said stay and extending laterally therefrom, a disk pivotally mounted on the outer end of said arm, said disk having a plurality of pairs of spaced apertures therein, each adapted to receive the securing prongs of a given insignia or ornament, thereby to facilitate accurately locating the insignia or ornament upon the collar wing.
2. A device in accordance with claim 1, wherein said disk also has spaced embossings therein for receiving the elongated pin of a conventional pin-type ornament.
3. A device in accordance with claim 1, wherein said arm is made integral with the upper stay section.
4. A device according to claim 3, wherein said intermediate tubular section is provided at its upper end portion with vertically spaced lugs adapted to be wrapped about said upper section and said laterally extending arm, thereby to fixedly secure said arm to said tubular member.
5. In a device of the class described, an elongated member comprising dual telescopic sections connected together for axial movement, one of said sections having terminal means for engaging the fold at the upper edge of a collar wing, and the other of said sections having means for engaging the tip of the collar wing, means urging said sections into extended positions to secure the device to the collar wing, an arm extending laterally from said elongated member, and a plate-like element pivoted to the outer end of said longitudinally extending arm and

having spaced means therein for receiving the usual securing pins or prongs of a given insignia or ornament.

6. In a device of the class described, an elongated member comprising dual telescopic sections connected together for axial movement, one of said sections having terminal means for engaging the fold at the upper edge of a collar wing, and the other of said sections having means for engaging the tip of the collar wing, means urging said sections into extended positions to secure the device to the collar wing, an arm extending laterally from said elongated member, and a plate-like element pivoted to the outer end of said longitudinally extending arm and

having a plurality of pairs of spaced apertures therein for receiving the usual securing pins or prongs of a given insignia or ornament.
